US0D1094403S

(12) **United States Design Patent** (10) **Patent No.:** **US D1,094,403 S**
(45) **Date of Patent:** **** Sep. 23, 2025**

(54) **WEARABLE DEVICE WITH GRAPHICAL
USER INTERFACE**

(71) Applicant: **Apple Inc.**, Cupertino, CA (US)

(72) Inventor: **Aled Williams**, Llandeilo (GB)

(73) Assignee: **Apple Inc.**, Cupertino, CA (US)

(**) Term: **15 Years**

(21) Appl. No.: **29/913,221**

(22) Filed: **Sep. 28, 2023**

Related U.S. Application Data

(63) Continuation of application No. 29/828,421, filed on Feb. 25, 2022, now Pat. No. Des. 1,002,671, which is a continuation of application No. 29/718,135, filed on Dec. 20, 2019, now Pat. No. Des. 944,859, which is a continuation of application No. 29/619,687, filed on Sep. 29, 2017, now Pat. No. Des. 870,774.

(57) **CLAIM**

The ornamental design for a wearable device with graphical user interface as shown and described.

DESCRIPTION

FIG. 1 is a front view of a wearable device with graphical user interface showing the claimed design;

FIG. 2 is another embodiment thereof; and,

FIG. 3 shows an environmental wearable device to which the designs of FIGS. 1-2 may be applied.

The outermost broken lines FIGS. 1-2 show a wearable device having a display screen, and form no part of the claimed design.

The broken lines in FIG. 3 show environment, which forms no part of the claimed design.

1 Claim, 2 Drawing Sheets
